CAR TOP CHORD

William C. Sleeman, Birmingham, Ala., assignor to Pullman-Standard Car Manufacturing Company, Chicago, Ill., a corporation of Delaware

Application January 20, 1954, Serial No. 405,122

3 Claims. (Cl. 105—406)

This invention relates to a railway hopper or gondola car and specifically to an improved top chord construction.

With respect to gondola cars where clam shell-like buckets are used for loading and unloading, a strong top chord construction and one with no protruding portions is imperative. The constant threat of the bucket striking the top chord coupled with the actual amount of striking deems necessary the aforementioned features as distortion of the top chord would weaken the side sheet adjacent the distorted area and cause eventual failure of the entire side.

And likewise with respect to a hopper car, a structurally strong top chord construction is necessary, particularly where a side-vibrating shake-out device is used.

Thus, the principal object of this invention is to provide a top chord construction having improved structural strength.

Another object of this invention is to provide a top chord construction having improved structural strength and yet capable of efficient and economical manufacture and assembly.

A further object of this invention is to provide a top chord construction for use with either a gondola or hopper car, fulfilling the structural and performance requirements of each.

These objects and other objects will become apparent from the following description and accompanying drawings wherein:

Fig. 1 is a fragmentary, broken, side elevational view of a railway gondola car embodying the present invention;

Fig. 2 is a top plan view of the car in Fig. 1;

Fig. 3 is a vertical sectional view on the line 3—3 of Fig. 1; and

Fig. 4 is a vertical sectional view of the present invention taken on the line 4—4 of Fig. 1.

It is to be noted that while the invention is shown and described in one embodiment, it is not to be so limited and that modifications of this invention may be had without varying the spirit and scope of the objects as defined in the appended claims.

Referring to the drawings, a gondola railway car having a side 10 supported by a side sill 11, top chord arrangement 12, end plate 13, and end sill 14 is depicted.

The floor supporting structure at the crosstie is of the usual arrangement (Fig. 3) wherein a floor plate 15 is secured to a side sheet 16 by usual means and rests at its ends on a gusset plate 17 connecting the plate 15 with the I shaped crosstie beam 18. A supporting plate 19 is secured between the base of the crosstie 18 and the side sill 11.

Side posts 20 are longitudinally spaced along the outside of the side sheet 16, are secured thereto, and form a right angular basis of support therewith for the top chord 12. Lading strap anchors 21 may be secured to the side posts 20. A corrugated end sheet 22 is secured to the end sill 14 and the end plate 13 and wraps around the edge of the end side sheet 16.

The top chord arrangement 12 comprises a small upwardly facing channel beam 23 and a larger downwardly

2

facing channel beam 24. Tubular spreaders 25 may be inserted which act to separate the channel beams and also provide openings along the top chord for applying lading strap anchors or bolts for lading blockings. As a portion of the top chord is cut away for a ladder (not shown) an extension plate 26 is provided. The legs 23a of the beam 23 and the legs 24a of the beam 24 are of approximately equal cross-sectional length and width. By overlapping the legs 24a over the legs 23a, approximately a distance equal to the cross-sectional width of either leg 23a or 24a, the adjacent legs may be secured by weld seams 27, only a single automatic welding pass being necessary for both weld seams. Lading strap anchors 28 may be secured to an outer leg 23a and an inner leg 24a, being in approximately the same vertical plane of the side sheet 16, offers a generally flush surface on the inside of the car.

Thus, a structurally strong top chord is provided which offers no protruding parts on which a clam shell-like bucket might catch, which offers a generally flush inner car surface adjacent the top, and which, by being adaptable to a single welding operation, is structurally stronger and not as subject to distortion as a top chord having individually made welds.

What is claimed is:

1. In an open top railway car, a side sheet, a side post secured to said sheet, the top of said post forming with said sheet a right angular seat, and a top chord inserted on said seat and comprising an upwardly facing channel member secured to said sheet and said post, and a downwardly facing channel member secured to said upwardly facing member in an overlapping manner and forming therewith a box-like arrangement.

2. In an open top railway car, a side sheet, a side post secured to said sheet, said sheet extending vertically a distance beyond the top of said post, and a top chord comprising an elongated horizontally disposed upwardly facing channel-like member having a base, an inside leg and an outside leg, said base being secured to the top of said post, and said inner leg being secured to said sheet and extending thereabove, a U-shaped lading strap bracket secured to said outer leg, an elongated horizontally disposed downwardly facing channel-like member secured to said upwardly facing member by welding and in an overlapping manner, and a tubular-like spreader inserted between said members.

3. In a railway car, a side sheet, a side post, and a top chord secured to said sheet and said post comprising a horizontally disposed upwardly facing first channel-like member having legs, and a horizontally disposed downwardly facing second channel-like member having legs, the legs of the second member being of approximate equal cross-sectional length and width with the legs of the first member and overlapping the latter legs a distance substantially equal to the width of a leg, and a weld seam securing each adjacent pair of legs, said seams being in the same horizontal plane.
